UNITED STATES PATENT OFFICE

2,613,401

TILTING DOOR

Jacob Wieland, Gorinchem, Netherlands, assignor
to De Vries Robbe & Co. N. V., Arkelschedijk,
Gorinchem, Netherlands

Application April 16, 1949, Serial No. 87,990
In the Netherlands April 2, 1948

4 Claims. (Cl. 20—16)

1

The invention relates to a tilting door, especially to doors with a relatively large surface.

Constructions are known, with which the lower side of the door can be moved upwards and then be guided along the plane being closed by the door in vertical position.

In order to be able to move such like doors easily up and down, up to now counterweights have been used, which are connected to cables or the like.

The invention has for its object to provide a construction, which makes the use of cables with counterweights superfluous. This has the advantage, that the possibility of breaking of a cable has been eliminated, that no space for the cables and the counterweights needs to be provided and that generally there are not the objections connected with the use of said cables with counterweights.

According to the invention the door is suspended on a structure by means of hinges on one or more supporting arms, pivoted to one point situated between the lower edge of the door and the centre of gravity of the door, with which the length of the hinged arm is equal to half the distance from the lower supporting edge of the door, which is guided in the plane of the door opening, to the centre of gravity of the door.

In the accompanying drawing the invention is illustrated.

The opening 1 in the wall 2 of a structure can be closed by means of the tilting closing member 3. In order to open the door-opening the lower part 4 of the door or closing member 3 is moved upwards and as usually the door can be guided with a roller along a guide. The door is suspended on a hinged arm 5, which is attached to the wall at 6 and to the door at 7. The point 7 is situated between the lower edge 4 and the centre of gravity *z* of the door. It is clear that in this way some isosceles triangles with sides *a* are formed. The centre of gravity *z* of the door moves when opening and closing the door along a horizontal line 6—*z*. The moment of the weight of the proper door *p* with respect to the point *z* is equal to the moment of the weight *p* with respect to point *z*. Thus *p* is *p* $\times$ *c*, whereas *p* + *p* is equal to *p*. The weight *p* can be considered as the weight of the door without the special making heavier to be discussed hereafter, namely the weight of the door from the lower part to the centre of gravity *z*. *p* is the weight of that part of the construction, located at the other side of the centre of gravity *z*.

2

In the embodiment illustrated in the drawing is supposed, that the lower part of the door is guided along the plane of the door when it is moved upwards. However point 4 can also be situated at some height above the lower limitation line of the door. This means that when moving the door upwards the lower part of same will project over some distance outside the plane of the door-opening. Moreover in this case the distance of the guiding point 4 to point 7 must also be equal to the distance of point 7 to *z* (*a*).

In order to be able to use the construction efficiently care is taken that the part of the door closing the opening 1 in the wall, is light, e. g. from aluminium plate. In a closed position of the door the point 8 of the door will be situated opposite or near the upper side 9 of the opening. In order to provide that the centre of gravity *z* comes at the indicated place, the panels of the door are preferably extended beyond point *z*, whereas a weight is arranged between these panels, which is rigidly connected with the door. The weight of the panels beyond the point *a* together with the extra weight 10 forms *p*, whereas *p* is formed by the door part between the points 4 and 8 and the panels extending from 8 to *z*.

It is advantageous to make the part 4—8 of the door as light as possible. Therefore it is advisable to provide projecting door panels with the weight 10 arranged between them as a rigid profile frame. The rigidity against deformation is then especially obtained by the great torsional rigidity of the weight.

What I claim is:

1. A closure means for an opening in a substantially vertical structure, comprising, in combination, a tiltable closing member movable between a substantially vertical closing position for closing said opening, and an opening position, said closing member having an upper edge and a lower edge, said lower edge being mounted on said structure slidable in a substantially vertical plane; at least one supporting arm adapted to be pivotally secured at one end thereof to said structure in said vertical plane, and pivotally secured at the other end thereof to said closing member at a pivoting point spaced from said lower edge for a distance equal to the length of said supporting arm; and weight means secured to said closing member in the region of said upper edge and so arranged and dimensioned that the combined center of gravity of the entire closure means is located in the plane of said closing member spaced from said lower

edge of the same a distance equal to twice the length of said supporting arm, so that said center of gravity moves along a horizontal line while said closing member moves between said closing and opening positions.

2. A closure means for an opening in a substantially vertical structure, comprising, in combination, a tiltable closing member movable between a substantially vertical closing position for closing said opening, and an opening position, said closing member having an upper edge and a lower edge; roller means secured to said closing member in the region of said lower edge and being movable on said structure in a substantially vertical plane; at least one supporting arm adapted to be pivotally secured at one end thereof to said structure in said vertical plane, and pivotally secured at the other end thereof to said closing member at a pivoting point spaced from said lower edge for a distance equal to the length of said supporting arm; and weight means secured to said closing member above said upper edge, and so arranged and dimensioned that the combined center of gravity of the entire closure means is located in the plane of said closing member spaced from said roller means a distance equal to twice the length of said supporting arm, so that said center of gravity moves along a horizontal line while said closing member moves between said closing and opening positions.

3. A closure means for closing and opening in a vertical structure, comprising, in combination, door means, including a door adapted to close said opening by sliding with the lower edge thereof in a vertical plane along said structure from a horizontal opening position to a vertical closing position, a weight means, and means securing said weight means to said door spaced from the top edge at such distance that the combined center of gravity of said door means is located in the upper portion of the same; and supporting means adapted to be pivoted at one end thereof to said structure in said vertical plane, said supporting means having substantially the length of half the distance between

5 said lower edge of said door and said center of gravity, and being pivoted at the other end thereof to said door at a point located at equal distances from said lower edge of said door and said center of gravity, so that said center of gravity moves along a horizontal line during closing and opening of said door.

10 4. A closure means for closing and opening in a vertical structure, comprising, in combination, door means, including a door adapted to close said opening by moving from a horizontal opening position to a vertical closing position, roller means rotatably secured to said door in the region of said bottom edge and moving in a vertical plane along said structure during closing and opening of said door, a weight means, and side panels secured to said door and projecting over the top edge of said door and securing said weight means to said door spaced from the top edge of the same, said weight means being so dimensioned as to locate the center of gravity of said door means above said top edge of said door; and a pair of supporting arms having one pair of ends adapted to be pivoted to said structure in said vertical plane, said supporting arms having substantially the length of half the distance between said roller means and said center of gravity, and being pivoted at the other pair of ends thereof to said door at points located at equal distances from said roller means and said center of gravity so that said center of gravity moves along a horizontal line during closing and opening of said door.
